UNITED STATES PATENT OFFICE.

JEROME B. JUDKINS, OF WINCHESTER, MASSACHUSETTS.

DESIGN FOR A ZITHER.

SPECIFICATION forming part of Design No. 21,275, dated January 5, 1892.

Application filed November 28, 1891. Serial No. 413,451. Term of patent 7 years.

To all whom it may concern:

Be it known that I, JEROME B. JUDKINS, of Winchester, in the county of Middlesex and State of Massachusetts, have invented and produced a new and original Design for Zithers or for Similar Stringed Musical Instruments, of which the following is a specification, reference being had to the accompanying photographic illustration, forming a part thereof.

The photograph or illustration represents a perspective view of a zither or similar stringed musical instrument, showing the shape or configuration of my design in contour or outline.

The leading feature of my design consists in the reverse-curved or "ogee" end A adjacent to the string-keys F and formed on an obtuse angle or obliquely to the long straight side B, which is formed parallel with the short side C, which extends from the curved point to the acute angle D, which extends to

the short square end E, which is formed at a right angle to the said long straight side B, as represented in the photographic illustration. The contour-line of the curved end portion A harmonizes with the several straight and angle lines, thus presenting to the eye a pleasing effect when viewed as a whole outline of a "zither" or other similar stringed musical instrument.

Having thus described my design, I claim—

The design for a zither herein shown and described, the same comprising the configuration of the curved ogee end A, the long straight side B, the short straight side C, the acute angle D, and square right-angled end E, arranged relatively to the string-keys F as set forth.

JEROME B. JUDKINS.
